UNITED STATES PATENT OFFICE.

CHARLES M. CROOK, OF CHICAGO, ILLINOIS, ASSIGNOR TO STROMBERG ELECTRIC COMPANY, OF CHICAGO, ILLINOIS, A CORPORATION OF MAINE.

TIME RECORDER.

Application filed December 29, 1922. Serial No. 609,573.

My invention relates to workmen's time recorders. More specifically it relates to a type of time recorder which operates a card having a number of columns thereon designated "In" and "Out" and also having spaces arranged one above the other on the card for a number of days, usually enough to take care of a half month. The card usually has a column for "In" in the morning; "Out" in the morning; "In" in the afternoon; "Out" in the afternoon; "In" for overtime; and "Out" for overtime.

The workman on coming in in the morning inserts his card into the machine, and operates a lever or other suitable operating means, which will cause to be typed in the proper place on the card the time at which the workman comes in. Similarly on going out at noon, he inserts the card into the machine, and operates the lever, causing the time at which he goes out at noon to be printed or typed on the card; and so on for the other columns for afternoon "in," afternoon "out" and so forth.

Means are provided whereby at a certain time in the morning, a shift will be made which will cause the type to be done in the "Out" column rather than in the "In" column, the time of this shift being arbitrarily determined, at a time when it is presumed that most of the workmen will be in and that after this time all or the majority of the cards should be typed in the "Out" column.

In the event, however, that a workman comes in very late, after this automatic shift has taken place, he would still want to have his card typed in the "In" column to show the time he arrived, rather than in the "Out" column where the shift would naturally cause it to be placed.

In the event of such late arrival, the workman goes to the foreman, and secures from him a key which enables him to manually make a shift which will enable him to have his card printed in the "In" column rather than in the "Out" column.

In order that the times of arrival and departure will be printed on different lines on different succeeding days, time controlled

means are provided operable automatically 50 once a day for causing the vertical position of the card to be varied from day to day, to cause the date to be printed in the proper place on the card.

One of the objects of my invention is to 55 provide an improved time recorder of the type indicated above, having shiftable type mechanism controlled by time controlled mechanism. A further object of my invention is to provide shiftable time controlled 60 type mechanism in which the transmission for the type mechanism is operable in any position to which it is shifted. A further object of my invention is to provide a time recorder of the type indicated above in which 65 various mechanisms which go to make up the machine are mounted on sub-frames which are detachable as a unit. A further object of my invention is to provide improved means for positioning the card vertically. A further object of my invention is to provide improved means for preventing 70 blurring of the typing. A further object of my invention is to provide an improved time recorder of the type indicated above, 75 which will be durable and efficient in use. Further objects will appear in the detailed description to follow and from the appended claims.

In the drawings, in which an embodiment 80 of my invention is shown,

Fig. 1 is a perspective view of the complete machine, showing a card about to be inserted;

Fig. 2 is a front elevation of the recorder 85 with the casing removed;

Fig. 3 is a vertical sectional view of the machine on the line 3—3 of Fig. 2;

Fig. 4 is a vertical sectional view of the machine on the line 4—4 of Fig. 2;

Fig. 5 is a top plan view of the machine;

Fig. 6 is a horizontal sectional view looking up substantially on the line 6—6 of Fig. 2;

Fig. 7 is a vertical sectional view substantially on the line 7—7 of Fig. 2;

ing up substantially on the line 9—9 of Fig. 2; Fig. 10 is a vertical sectional view substantially on the line 10—10 of Fig. 5;

Fig. 11 is a vertical sectional view substantially on the line 11—11 of Fig. 10;

Fig. 12 is a vertical sectional view substantially on the line 12—12 of Fig. 8;

Fig. 13 is a vertical sectional view substantially on the line 13—13 of Fig. 5;

Fig. 14 is a vertical section substantially on the line 14—14 of Fig. 3;

Fig. 15 is a vertical sectional view substantially on the line 15—15 of Fig. 2; and

Fig. 16 is a sectional view showing a form 15 of ball bearing used.

Referring now to the drawings in detail, the construction shown therein comprises time controlled mechanism A (Figs. 4 and 5) operable by the workman for typing on a card 20 B the time of day at which the workman arrives or departs; time controlled mechanism C (Fig. 11) for shifting the printing mechanism laterally from "in" to "out" position or vice versa at predetermined intervals; 25 mechanism D (Figs. 1, 3 and 4) operable by the workman (when authorized by the foreman) for manually shifting the printing mechanism laterally when desired from "in" to "out" position or vice versa; time controlled 30 mechanism E (Figs. 7 and 12) operable once a day for causing the vertical position of the card to be varied from day to day to cause the dates to be typed in the proper space on the card B; and indicating means F (Figs. 1, 2, 35 and 7) operable once a day for indicating the date corresponding to the space on the card B which will receive the impression.

In order to enable the construction and operation of the machine to be better understood, 40 a description of the card on which it operates will now be given.

This card B (Fig. 1) has a space 20 for the workman's name, and a space 21 for the workman's number, and is ruled to provide a number 45 of horizontal rows for the different days, and a number of vertical columns headed "Morning in"; "Morning out"; "Afternoon in"; "Afternoon out"; "Overtime in"; "Overtime out". As stated above, there are usually 50 enough horizontal rows on the card to provide for a half month. The card shown has sixteen horizontal rows.

Type mechanism shiftable for "In" and "Out".

55 A feature of the machine is that it comprises a bodily shiftable type mechanism which is automatically shifted at intervals during the day to shift the type mechanism to cause the impression to be made in different columns at different times of the day. The times at which the type mechanism is shifted laterally may be determined arbitrarily by the foreman or superintendent, a suitable time controlled mechanism being provided where-

by the automatic shift is effected at the desired time.

As indicated above, means operable by the workman (when authority is obtained from the foreman or superintendent) are provided whereby the type mechanism may be shifted 70 manually independently of the automatic shifting.

The shiftable type mechanism itself will first be described before describing the automatic control and the manual control for 75 shifting it, referring to Figs. 2, 3, 4, 5, 10 and 13.

This type mechanism comprises a laterally shiftable carriage 22 mounted to be shifted laterally on supporting and guide rails or 80 rods 23 and 24 respectively. A pair of grooved wheels or rollers 25 mounted on the carriage 22 and straddling the guide rail 23 form the main anti-friction support for the type carriage. The auxiliary rollers or 85 wheels 26 and 27 which engage the guide rod 24 serve to additionally support and position the type carriage in its travel. The guide rollers 26 which engage the underside of the guide rod 24 hold the front portion of the 90 type carriage against upward displacement while the guide rollers 27 which engage the rear side of the guide rod 24 hold the type carriage 22 against forward tipping movement. Because of the provision of these rollers 25, 95 26 and 27, very little force is required to shift the type carriage laterally, so that it can easily be shifted by means of a magnetically operated secondary clock mechanism. It is here stated also that ball bearings are provided for all of the rotatable parts. Because 100 of this provision, very little force is required to rotate these parts, and the magnetically operated secondary clock mechanism is able to operate the clock driven parts readily in 105 addition to shifting the type carriage.

This ball bearing construction, shown in detail in Fig. 16, comprises a pair of cup members 27^a and 27^b, which telescope together to form a ball race, and a pair of spiders 27^c and 27^d, which fit between and embrace the ball race, and the legs of which interfit with each other and may be clinched over as indicated at 27^c and 27^d, to secure the entire construction 110 in position in the opening of the supporting 115 plate in which the ball bearing is mounted.

The type carriage (shown removed from the rest of the mechanism in Fig. 13) comprises three type wheels 28, 29 and 30, respectively, the type wheel 28 being provided with 120 characters indicating the days of the week; the type wheel 29 being provided with characters indicating the hours of the day; and the type wheel 30 provided with characters indicating the minutes of the hour.

These type wheels are driven from a spur gear 31, mounted on the carriage, this pinion being clock controlled, and suitable trans-

mission mechanism 32 (not necessary to be described in detail) being provided from the spur gear 31 to the type wheels so that the proper characters to represent the day of the 5 week, the hour of the day and the minute of the hour, will be presented at the proper time for cooperation with the elongated hammer face 33.

It is here stated that this hammer face is 10 elongated in order that some portion of it will cooperate with the characters on the type wheel, no matter to what lateral position the type carriage may be shifted.

In order to connect up the driving gear 31 15 for the type wheels with the clock controlled mechanism, I provide an elongated pinion 34, with which the type wheel drive gear 31 meshes, this type wheel drive gear 31 being shiftable laterally along the elongated pinion, 20 as the type carriage is shifted.

In order to give a general idea of the construction of the type carriage, it is stated that it comprises a sub-frame 35 having a pair of spaced side-plates 36 and 37, on which the 25 guiding and supporting rollers 25, 26, and 27, are mounted and between which the type wheels 28, 29 and 30, are mounted, and on which the transmission 32 from the type wheel drive gear 31 to the type wheels is 30 mounted.

The time controlled mechanism for operating the elongated drive pinion 34 will now be described, referring particularly to Figs. 2, 3, 4, 5, 6 and 7. This time controlled mechanism comprises an electromagnet 38, (energized periodically, usually once a minute) having an armature 39 pivotally mounted at 40, an upwardly extending arm 41, mounted to oscillate with the armature 39, a pawl 42, pivotally mounted at 43 on the upper end of the vertical arm 41, a ratchet wheel 44, driven by the pawl 42, a shaft 45, on which the ratchet wheel 44 is mounted, extending across from one side to the other of the machine, a 45 spur gear 46, mounted on the shaft 45, and meshing with the elongated pinion 34 previously described, and a spring 46^a for returning the armature 39 upon de-energization of the electromagnet 38, to cause the pawl 42 to 50 actuate the ratchet wheel 44, (Figs. 2 and 4). A spring pressed pawl 47 is provided, engaging the underside of the ratchet wheel 44, to prevent backward movement of this ratchet wheel. The pawl 42 is provided with a 55 downwardly extending arm 48, which engages a stop 49, to prevent overtravel of the ratchet wheel. This arm 48, engaging the stop 49, at the latter part of the movement of the arm 41, holds the pawl 42 firmly in engagement with the ratchet wheel, and will not permit the ratchet wheel to travel ahead of the pawl, as it might do, because of its momentum, if it were not thus held.

The transmission from the pivoted armature 60 65 39 to the elongated pinion 34, and from

the elongated pinion 34, to the type wheels, may be so designed that each oscillation of the armature of the electromagnet will cause the minute type wheel to be advanced one minute.

I will now describe a self-contained unit 70 which comprises the time controlled mechanism for controlling the lateral shift of the type carriage, the manual control for the lateral shift of the type carriage, and the dial 75 and hands of the clock. In describing this mechanism, reference may be made particularly to Figs. 1, 2, 3, 5, 9, 10 and 11.

The mechanism for shifting the type carriage 22 laterally comprises a horizontal rack 80 50 mounted on the front of the carriage, a spur gear 51 meshing with the rack 50, a spur pinion 52 rotatable with the spur gear 51, a lever 53 (Fig. 11) pivoted at 54, and having a segmental gear portion 55 meshing with the 85 pinion 52, a cam controlled lever 56 also pivoted at 54, a coil tension spring 57, tending to hold the lever 53 against the cam controlled lever 56 at the point 57, a plurality of independently adjustable cam pieces 58, 59, 60, 90 61, 62 and 63, for controlling the rock lever 56, a coil tension spring 64, (Fig. 11), for holding the point 65 of the rock lever 56 over against the cam pieces 58, 59, etc., transmission 66 between the elongated pinion 34 previously referred to and the cam pieces 58, 95 59, etc., a manually operable button 67, and transmission means 68 between this manually operable knob or button 67 and the rock lever 53, which does not interfere with the time controlled operation of the rock lever and which can be used to operate this rock lever 100 53 independently of the time controlled mechanism.

The transmission between the time controlled elongated pinion 34 and the compound cam 69 comprising the cam pieces 58, 59, etc., is so designed that this compound cam 69 will be rotated once every twenty-four hours.

As this compound cam is thus slowly rotated, the point 65 of the rock lever 56 will 105 successively drop from one cam piece onto the following cam piece, each drop of this arm effecting a shift of the type carriage. After the point 65 of the rock lever has 110 dropped off from the last cam piece 63, cam piece 58 comes into engagement with the roller 70 mounted on the lower end of the rock lever 56, and gradually restores this rock lever to original position, thus returning 115 the type carriage to its original position ready to start the next day. This return operation of the type carriage may take place during the hours when there are no workmen coming in or out, say between the hours of midnight and 7 a. m.

For convenience in setting the independently adjustable cam pieces, I may provide a dial 71, having indicated thereon the hours 120 of the day, so that the cam pieces can be set 130

to cause a shift at the desired hour. The cam pieces are adjustable angularly about the pin 72, and are held in any position to which they may be adjusted by means of a clamping disc 5 or plate 73, and a pair of clamping screws 74, which extend through holes in the clamping plate 73 and through arcuate slots (not shown) in the various cam pieces, and are threaded into a rear clamping disc 75, the various cam pieces being set in the desired position and clamped between the two clamping discs or plates 73 and 75, by means of the clamping screws 74.

The transmission means from the elongated pinion 34, to the compound cam 69, comprises a spur gear 76, (Fig. 11), meshing with the elongated pinion 34, a bevel pinion 77, rotatable with the spur gear 76, a bevel gear 78, meshing with the bevel pinion 77, 15 a spur pinion 79, rotatable with the bevel gear 78, a spur gear 80, meshing with the spur pinion 79, a spur pinion 81, rotatable with the spur gear 80; a spur gear 82, meshing with the spur pinion 81, and a shaft 83, 20 on which the spur gear 82 is mounted, and on which the compound cam 69 also is mounted so that this compound cam 69 rotates with the spur gear.

The transmission 68 from the manually operable button 67 to the rock lever 53 which carries the gear segment, comprises a rock member 84, (Figs. 4 and 11), mounted on the inside of the cover 85, and oscillatable with the manually operable knob, a pair of oscillatable levers 86 and 87, oscillatable by means of the rock member 84, a rock arm 88, located between the oscillatable rock levers 86 and 87, and operable by them alternatively, and a link 89, pivotally connected at one end 90 with the rock arm 88 and at the other end with the rock lever 53 which carries the gear segment 55.

A torsion spring 91 extends between the rock levers 86 and 87, and normally holds the arms 92 and 93 of these rock levers against the stop 95, and thus normally holds the pins 96 and 97 on these rock arms 86 and 87 out of engagement with the rock arm 88.

However, either one of the rock levers 86 or 87 can be moved to operate the rock arm 88 when desired by means of the rock member 84, which has a pin 98 thereon, located between the extensions or arms 92 and 93, so that when this rock member 84 is turned in one direction it will bring the rock lever 86 into engagement with the rock arm 88, and when it moves in the other direction, it will bring the other rock lever 87 into engagement with the rock arm 88.

Thus by turning the manually operable knob 67 in one direction or the other, the rock lever 53 which carries the gear segment can be oscillated in one direction or the other, and thus the type carriage 22 shifted in one direction or the other.

This manual adjustment of the type carriage 22 can be effected independently of the time controlled cam controlled movement of the type carriage, because of the spring connection 91 between the rock lever 86 and the rock lever 87, and because of the fact that the rock lever 56 can be moved away from engagement with the compound cam 69 by stretching the spring 64 which holds this rock lever 56 against the cam 69.

In order to give a general idea of the structure, it is stated that the transmission 66 from the elongated clock controlled pinion 34 to the compound cam 69 is mounted between a pair of substantially parallel plates 99 and 100, 70 which in turn are mounted on a supporting casting or bracket 101, secured to the main side plates 102 and 103 of the machine.

In order to indicate the time of day, a clock dial 104 may be mounted in front of the bracket 101, the hands 105 and 106 being driven from a spur pinion 107 mounted to rotate with the bevel gear 78, by suitable transmission not necessary to be described in detail.

In order to indicate the "in" and "out" position of the type carriage, I provide a pointer 108 on the type carriage 22, which co-operates with an indicating plate 109 mounted on the bracket 101, this indicating plate 109 bearing the designation "Morning in", "Morning out", "Afternoon in", "Afternoon out", "Overtime in" and "Overtime out". This enables the workman to know in what position the type carriage 22 is set, and enables him to shift the type carriage, when he has the authority of the superintendent, to bring the type carriage to the proper position.

Hammer mechanism.

The hammer mechanism is probably best shown in Figs. 3, 4, and 12, although it is also shown in Figs. 2, 5, 6, and 8. The hammer 110 is withdrawn from the type wheels against the tension of the coil tension springs 111, when the workman presses down on the handle 112 and is suddenly released at a certain point in the movement of the handle, to permit the hammer to snap forward under the action of the springs 111, to cause the elongated rubber face 33 of the hammer to snap the card B, over against the inked ribbon 113, which runs between the type wheels and the card B.

The springs 111 do not directly bring the hammer face against the card, the final impact movement of the hammer being effected solely by the momentum of the hammer, and indeed against the action of a pair of springs 114, which act immediately after the impact to cause a quick rebound or withdrawal of the hammer face from the card.

In order to enable this "momentum movement" of the hammer to be effected, the hammer is made in two parts, pivotally connected together at 115, (Fig. 12) these two pivotally

connected portions being provided with engageable shoulders 116 and 117 normally held in engagement with each other by means of the springs 114 referred to above.

5 Stop means hereinafter described in detail are provided for limiting the distance to which the springs 111 can move the lower portion 118 of the hammer. This stopping of the movement of the portion 118 of the hammer under the action of the spring 111 takes place before the hammer face has engaged the card B, so that the remaining movement of the hammer face is due to the momentum of the upper portion 119, which 15 causes the upper portion 119 of the hammer to swing forward about its pivot 115, and against the action of the springs 114, as indicated in Fig. 12, until the rubber face 33 of the hammer engages the card B, and snaps 20 it over against the ribbon 113, causing the day, hour and minute to be impressed on the card. Fig. 12 shows the shoulders 116 and 117 slightly apart, showing that the lower portion 118 of the hammer has come to a stop, 25 and that the upper portion 119 has swung forward due to its own momentum against the action of the springs 114. In order to limit the distance to which the upper portion of the hammer can travel due to its own momentum, I provide a pair of stops 120 and 121, (Fig. 8) one at each side of the hammer face, located in the path of the cushion stop members 122 and 123, which are secured to the opposite sides of the upper end of the 35 upper portion 119 of the hammer. (See Figs. 4 and 8.) The stop members 120 and 121 are metal pins rigidly secured to the side frame members 102 and 103. Each of the cushion stop members, mounted on the hammer, 40 which cooperates with the rigid metal stop members, comprises a metal pocket 124 rigidly secured to the hammer, in which is seated a cushion 125 of rubber or similar suitable material, the rubber extending some distance 45 outwardly beyond the pocket, so as to engage the stop member and limit the distance which the upper end of the hammer can move because of its momentum. These stop members not only serve to limit the distance which 50 the hammer can move, but also serve to keep the hammer head in alignment throughout its length, at the time when the printing is being done. Referring further to this Figure 12 it will be seen that as soon as the hammer face 55 strikes the card B, the upper portion 119 of the hammer will rebound or be jerked back by the tension of the springs 114, until the shoulders 116 and 117 are again in engagement with each other.

60 I will now describe the transmission from the handle 112 to the lower portion 118 of the hammer. This comprises a lever 126 formed of a pair of metal bars secured together, on which the handle proper 112 is mounted, a 65 shaft 127 (Fig. 12) on which the lever 126

is mounted for pivotal movement, a four-toothed ratchet wheel 128, mounted on the shaft 128^a, pawl mechanism 129 acting between the lever 126 and ratchet wheel 128, whereby each oscillation of the lever 126 causes a quarter turn of the ratchet wheel 128, a pair of cam wheels 129^a, (Fig. 4) each having four similar cam portions 130, also mounted on the shaft 128^a and rotatable with the four-toothed ratchet wheel 128, and a follower shaft 131, having a pair of rollers 132, engageable with the cam wheels 129^a, and mounted on the rock levers 133, which are secured to and rock with the lower portion 118 of the hammer. The springs 111 referred to above are connected to the rear ends of the rock levers 133, (Fig. 4), and act to hold the following rollers 132 in engagement with the cam wheels 129^a. As the cam wheels 129^a are rotated, the rock levers 133 are caused to rise gradually and then fall suddenly, the gradual rising movement effecting the retraction of the hammer and the sudden fall permitting the quick snapping forward of the hammer under the action of the springs 111.

The gradual lifting movement of the rock levers 133 is effected by the gradually inclined forward portion of the cam portions 130, the sudden drop being effected when the rollers 132 ride off the abrupt crest of the cam portion 130 and drop down onto the succeeding cam portion.

The pawl mechanism 129 for effecting the step-by-step movement of the ratchet wheel 128 and cam wheels 129^a comprises a pawl 134 (Fig. 12) pivotally mounted at 135 on the lever 112, which engages a tooth of the ratchet wheel on the downward movement of the hand lever; to effect the striking movement of the hammer, and a second pawl 136, also pivoted at 135, which engages a tooth of the ratchet wheel on the upward spring actuated movement of the hand lever, to cause a partial withdrawal of the hammer 110. A spring 137 is provided, connecting the two pawls, the purpose of which is to hold the pawls in engagement with the ratchet wheel 128 to cause them to properly engage the teeth of the ratchet wheel. A spring 138 is provided to return the hand lever—after it has been pressed down by the workman.

I will now describe a detail of the construction whereby I prevent the inked ribbon from blurring the card when the hammer is actuated. This comprises a thin flexible metal plate 139, secured at its lower end to the type carriage, (Figs. 10 and 12), extending across the rear of the type wheels to a point just below the point where the hammer strikes, and a second flexible plate 140, extending the full width of the card holder 141 and secured thereto, (Fig. 8), this flexible strip 140 being secured at its upper edge to the card holder, and having its lower free edge extending 136

downwardly to a point just above the point where the hammer strikes. As shown in Fig. 12, the upper edge of the flexible plate 139 and the lower edge of the flexible plate 140 are between the ribbon 113 and the card B with just space enough between them to permit the hammer 110 to drive a portion of the card B between these edges against the ribbon 113. The two flexible plates thus serve between them to properly position and guide the ribbon and to effectually prevent printing at any place except at that portion of the card between the lower edge of the flexible plate 140, and the upper edge of the flexible plate 139.

Without these guards, the printing on the card would be apt to be blurred, as the type both above and below the printing point might make a partial impression on the card, which would make the card very difficult to read.

As shown in Fig. 12, the lower strip 139 is offset slightly with respect to the flexible strip 140, the plate 139 being slightly further forward than the plate 140. The purpose of this is to prevent the lower edge of the card B from catching on the upper edge of the flexible plate 139 as it is being inserted. The flexible plate 140 will steer the lower edge of the card so that it will clear the upper edge of the flexible plate 139 when it is being inserted into the card holder.

Card holding and positioning mechanism.

I will now describe the means for holding and positioning the card, shown more particularly in Figs. 3, 4, 7, 8 and 12 and also shown in Figs. 2, 5 and 9. This comprises a pair of spaced vertical guides 142 and 143, having grooves 144 to receive the vertical side edges of the card B, a pivoted card rest 145 mounted on a rock shaft 145^a to oscillate therewith having a series of steps or rests 146, on which the lower edge of the card B rests, and time controlled mechanism 147 (Fig. 7), for controlling the movement of the pivoted card rest 145, so that on each succeeding day a different rest or step 146 will be brought into position for the lower edge of the card to rest on, so that on each succeeding day, the card will be inserted less far into the machine to cause the printing to be done in the proper place.

This clock controlled mechanism for causing a limited pivotal movement of the card rest 145 comprises a spiral cam 148, mounted on a shaft 149, and engaging a pin or stud 150, mounted on one of the side members 151 of the card rest, and transmission means 152 (Fig. 7) from the ratchet wheel 44, previously referred to, to the spiral cam 148, whereby the spiral cam 148 will be given a step-by-step advance each day sufficient to cause the pivoted card rest 145 to be moved to bring the succeeding steps into position in line with the card guides 142, 143.

This transmission mechanism 152 from the time controlled ratchet wheel 44, previously referred to, to the spiral cam 148 comprises a pinion 153 (Figs. 2 and 7), mounted on the same shaft as the ratchet wheel 44, to rotate therewith, a spur gear 154 meshing with the pinion 153, a small pinion 155, rotatable with the large spur gear 154, a spur gear 156, meshing with the pinion 155, an adjustable cam member 157, adjustably mounted on the spur gear 156, a rock lever 158, pivoted at 159, and having a downwardly extending follower portion 160 engageable by the cam member 157, a downwardly extending pawl 161 pivotally connected at 162 with the rock lever 158, a ratchet wheel 163 which is given a step-by-step movement by the downwardly extending pawl member 161, a shaft 164 on which the ratchet wheel 163 is mounted, a spur gear 165 mounted on the shaft 164 to rotate with the ratchet wheel 163, and a spur gear 166, meshing with the spur gear 165, and mounted on the same shaft 149 on which the spiral cam 148 previously referred to is mounted.

The construction is designed so that the large gear 156 revolves once each day. This brings the cam member 157 into engagement with the downwardly projecting follower portion 160 of the rock lever 158 once each day, and thus lifts this rock lever 158 once every day. A coil tension spring 168 is provided, connected at 169 to an upward extension 170 of the rock lever 158, for returning this rock lever 158 after it has been lifted by the cam member 157 and after this cam member 157 has moved far enough along to allow the downwardly extending follower portion 160 to drop down. As the follower member 160 drops down, the rock lever 158 falls and gives a downward movement to the pawl 161, which in turn advances the ratchet wheel 163 one step and through the transmission previously described causes the spiral cam 148 to be advanced one step, to bring a different step or rest 146 into operative position for supporting the lower edge of the card B which is to be inserted.

A pawl 171 is provided, pivoted at 172, and engaging the ratchet wheel 163 to prevent backward movement thereof. The pawls 171 and 161 are held in operative relation with respect to the ratchet wheel 163 by means of a coil tension spring 173, connecting the two pawls.

In order to prevent the ratchet wheel 163 from running ahead of the pawl 161, after this pawl has completed its movement, this pawl member is provided with a downwardly extending finger 174, which engages the shaft 164, to positively hold the point of the pawl 161 in engagement with the ratchet wheel 163 and thus prevent "overthrow" of the ratchet wheel.

The cam member 157 is adjustably mounted on a dial 175 secured to rotate with the gear

156, this dial being provided with numbers to indicate the hours of the day, so that the cam member 157 can be set wherever desired to cause the shifting of the card rest 145 to 5 take place at any time of day desired, preferably during a time when the machine will not be in use. This cam member 157 comprises a metal stamping shaped to provide a clamping portion 176 (Fig. 9) which 10 straddles the edge of the dial, as shown in Fig. 9, a clamping screw 177 being provided extending through one side of the clamping portion of the cam and threaded into the other side of the clamping portion, to draw these 15 side portions together, to cause them to firmly grip the edge of the dial 175. The dial 175 is provided at its periphery with an annular rib portion as indicated at 178, the clamping portion 176 of the cam member being provided 20 with bumped in portions 179 and 180 interfitting with this annular rib 178, to assist in positioning the cam member 157 with respect to the dial 175. To further assist in positioning the cam member 157 with respect 25 to the dial 175, a notched disc 181 (Figs. 7 and 8) is secured to the dial 175, the cam member 157 having a point 182, which can be fitted into one of the notches on the notched disc 181.

30 The adjustable cam 157 can be shifted to any position about the periphery of the dial 175 and can be held in this adjusted position by means of the clamping screw 177. Thus the cam member 157 can be set so as to cause 35 the card rest 145 to be shifted at any desired time of day or night.

In order to provide a visible indicator which will show the day of the month corresponding to the position of the card rest 40 145, I provide a rotatable cylinder 183, having on its cylindrical surface a series of numbers corresponding to the days of the month, these numbers being visible through a sight 45 opening 184 in the casing 85.

50 This indicating cylinder 183 is given a step-by-step movement corresponding to the step-by-step movement of the card rest 145, by means of transmission mechanism 185, from the shaft 145^a on which the card rest 145 is mounted to the shaft 186 on which the rotatable indicating cylinder is mounted. This transmission mechanism comprises a rock arm 187, secured to oscillate with the shaft 145^a, an upwardly extending link 188, 55 pivoted at its lower end at 188^a to the rock arm 187, a rock lever 188^a, pivotally mounted at 159, and having one arm 188^b pivotally connected at 189 to the vertically extending link 188, and having a segmental gear portion 190 on its other arm 191, and a pinion 192 meshing with the segmental gear portion 190 and secured to the shaft 186 on which the indicating cylinder 183 is mounted.

It will be noted that there are 16 steps or 60 rests on the card rest 145. It will also be

noted that the spiral cam 148 which controls the position of this card rest 145 terminates in an abrupt drop, which permits the card rest to drop back after the 16th day to the position which it occupied on the first day. 70

As indicated above, the cards are made out with spaces for 16 days, so that the card for the first half of the month will run from one to 16 and the card for the second half of the month will run from 17 to the end of the 75 month. It will be noted that the indicating cylinder 183 has two columns, the first column containing the numbers from 1 to 16 and the second column containing the numbers from 17 to 31. For the first half of the month 80 the number in the left-hand column visible through the opening 184 indicates the day of the month, and for the second half of the month, the number in the right hand column visible through the opening 184 indicates the 85 day of the month. The opening 184 is wide enough so that both columns are visible but the observer will of course know which column to read.

In order to return the card rack 145 and 90 the indicating cylinder 183 when the pin 150 on the card rack 145 is ready to drop off from the high point of the spiral cam 148, I provide a coil tension spring 193, having one end secured at 194 to the frame member 102 95 and its other end secured to the rock lever 188^a, at 195, (Fig. 7).

Ribbon feed.

Suitable mechanism, not necessary to be 100 described, in detail, is provided for slowly feeding the ribbon 113 back and forth, this mechanism being described and claimed in my copending application, Serial No. 578,517, filed July 29, 1922. In a general 105 way, this ribbon feed mechanism comprises a pair of spools 196 and 197, (Figs. 5 and 8), to which the ends of the ribbon 113 are secured, and mechanism operable by the handle 112, for giving a step-by-step motion to one or the other of the spools, the feed being automatically shifted from one spool to the other at the end of the travel of the ribbon. This mechanism comprises a link 198, (Figs. 8 and 12), pivotally connected 110 at 199 to a rearward extension 200 on the hand lever 126, and transmission mechanism 115 from the link 198 to the ribbon spools, whereby the desired operation of the ribbon spools is effected. 120

In order to give a general idea of the arrangement, it is here stated that the hammer and hammer controlling mechanism, the pivoted card rest and the card holder are mounted between the two main side frame plates 125 of the machine 102 and 103, these side frame plates being provided with bearings or supporting bearings for the various operating parts.

In order to adjust the machine to take care 130

of cards of different widths, I make the right hand side 201 (Fig. 8) of the card rack 145 adjustable laterally on the shaft 145^a on which it is mounted, and for the same purpose I also make the right hand guide 143 of the card holder adjustable laterally on the bars 202 and 203 on which it is mounted. The particular manner in which the side 201 of the card rack 145 is adjusted is shown somewhat in detail in Figs. 3 and 8. As shown therein, the shaft 145^a to which the side of the card rack is secured, is provided with a plurality of notches 204, spaced to receive the spaced flanges 205 and 206 (Fig. 8) on the foot portion of the side member 201 of the card rack 145. By slipping the flanges 205 and 206 of the foot portion out of one pair of notches and slipping them into another pair and then securing the foot portion in place on the shaft 145^a by means of a screw (not shown) the width of the card rack 145 may be adjusted to accommodate cards of different widths. The right hand guide 143 of the card holder can be adjusted laterally simply by slipping it along the supporting bars 202 and 203 on which it is mounted. It is held in proper spaced relation with respect to the other card guide by means of the strip or bar 207, to which the flexible guide plate 140 is secured, this bar being secured at its end to the guides 142 and 143 respectively.

In order to further position the side frames 201, of the card rest 145, the bar 203 on which the lower ends of the card guides 142 and 143 rest is provided with notches or grooves 208, (see Figs. 3, 9, and 12) which receive the edges of the arcuate portions 209 of the side frames 201 of the card rest 145, these arcuate edges traveling or sliding in the grooves or notches and being positioned thereby, whereby the side frames of the card rest are firmly held against lateral movement.

Referring particularly to Fig. 8 it will be noted that the side guides 142 and 143 of the card holder are positioned quite close to the respective side frames 201 of the card rest, so that there is no chance that the bottom edge of the card will fail to rest on the proper step on the card rest. This would not be the case, if the card rest steps were positioned some distance from the card guides, as then the flexure of the card might permit the lower edge of the card to slip past the step on which it should rest and engage a lower step.

Frame, base and casing.

The two main side frame members 102 and 103, which carry practically all of the mechanism, are secured to the base 210 by means of a pair of heavy pins or rods 211 and 212 which extend through holes at the top and bottom respectively of the side frame members, and through registering holes in heavy

lugs 213 and 214 (Fig. 4) secured to the base 210. This cast base is secured in vertical position and serves to support the whole machine.

The sheet metal casing 85 which completely encloses the working parts, is open on its back side and can readily be slipped over the machine and secured to the base 210 and locked in position.

The casing can be hooked onto the base by means of four hooks 215 (Figs. 3 and 15), secured to the inside of the casing, at suitably spaced points, which are engageable with four socket members 216, secured to the front of the cast base. The casing is hooked on simply by slipping it over the machine, bringing the hooks 215 just above the socket members 216 and then letting the casing slip down to allow the hooks 215 to enter the sockets 216. (See Figs. 1, 2, 3, and 15). 85

In order to lock the casing in position on the base, a pair of spring latch members 217 and 218 are provided (Figs. 3, 6, and 15), which engage underneath a pair of shoulders or catches 219 and 220 secured to the 90 cast base 210. Each of these catches is slidably mounted in a U-shaped frame 221, secured to the casing 85. A torsion spring 222 serves to hold the latch members in engaging position with respect to its catch. 95

In order to effect the release of these latch members 217 and 218 a key-controlled barrel 223 is provided having on its inner face a pinion 224, which rotates with the barrel 223, and engages a pair of slidable racks 225 and 226 (Figs. 3, 6 and 14). Suitable transmission from these slidable racks 225 and 226 to the slidable latches 217 and 218 is provided as shown in Figs. 3 and 6, each of these transmissions comprising a link 227, pivotally connected to one of the rack bars, a bell-crank lever 228, pivotally mounted at 229, and having one arm pivotally connected at 230 with the link 227, and a link 231, pivotally connected at 232 with the other arm of the bell-crank lever 228, and pivotally connected at 105 the other end to one of the latches 217, 218. 110

In order to release the latches, the foreman or whoever has charge, can insert the key into the lock barrel 223, and turn the lock barrel thereby turning the pinion 224 through the transmission described, thereby effecting the release of the latch members 217, 218. When these latch members are released, the casing can be removed simply by lifting up 120 on it and then pulling out on it, thereby releasing the hooks 215 from the socket members 216. 125

Lock for manual shift.

In order that the mechanism may be locked when desired, against manual shifting of the type carriage, I provide a lock 233 (Figs. 10 and 11) having a vertically sliding bolt 234, engageable in a notch 235 in the rock plate 130

84 previously referred to which controls the manual shifting of the type carriage.

In order to release the manually controlled knob 67, for manual shifting of the type carriage, the workman obtains from the foreman or whoever is in charge a key which he inserts into the lock 233, and turns to lift the bolt 234 out of engagement with the notch 235, thereby freeing the rock plate 84 for manual operation.

The casing 85 is provided with a suitable slot or opening 236 (Fig. 1) in alignment with the card holder 141 through which slot the card B can be inserted into the card holder.

15 Handle opening.

In order that the handle 112 may not interfere with the slipping on of the casing over the mechanism, I provide an opening in the front of the casing, (Fig. 14) through which the handle 112 protrudes when the casing is in position. When the casing is being put in place, the handle slips through this opening 237 in the casing and extends outside the casing when it is in position. In order to close this opening after the casing is in position, I provide a slidable plate 238 having an opening 239 therein, having an enlarged circular portion 240 and an elongated narrow portion 241. Cover plate 242 is provided having an opening therein, to provide clearance for the handle, this opening comprising an upper enlarged circular portion 244, and a lower elongated portion 245. The apertured plate 238 is slidable between the casing proper and this cover plate 242, and is frictionally held in any position to which it may be moved. When the casing is to be placed in position, the slidable plate 238 is moved to its upper position which brings the circular portions 240 of the opening in the slidable plate in registration with the circular portion 244 of the opening in the cover plate. This leaves a large circular opening through which the comparatively large handle 112 can pass as the cover is placed in position. After the cover has been hooked onto the cast base, the slidable plate 238 is then slipped down, moving the circular portion 240 of the opening in the slidable plate out of registration with the circular portion 244 of the opening in the cover plate thereby completely closing the front of the casing except for an opening formed by the elongated narrow portion 241 of the opening in the slidable plate and the elongated portion 245 of the opening in the cover plate. These elongated opening portions provide an elongated slot in which the narrow shank portion of the handle can move up and down as the handle is operated.

The openings in the casing through which the clock hands, the "In" and "Out" indicator, and the day of the month indicator are visible respectively, may be enclosed by suit-

able glass plates if desired, in order to keep 65 foreign substances out of the casing.

In order that a signal may be made when a workman arrives or departs, a bell 246 is provided which is struck by hammer 247, mounted on a spring arm 248, secured to the 70 type hammer 110. With this construction it is obvious that the bell will be struck every time the workman presses down on the hand lever to print on his card.

75 Detachable sub-frames.

As intimated above, certain mechanisms are mounted as units, on sub-frames, which sub-frames together with the mechanisms mounted thereon, are readily detachable from the main frame as units. One of these units is the type carriage, shown in Fig. 13, another is the mechanism for manually and automatically controlling the lateral shift of the type carriage, substantially as shown in Fig. 11 and another is the electromagnetic mechanism, comprising the electromagnet itself, the armature, the upwardly extending arm, the pawl mounted on the arm, and the sub-frame on which these parts are mounted.

Describing first the type carriage unit, this is a complete unit, including the sub-frame 35, the type wheels 28, 29 and 30, the type wheel drive gear 31, the type wheel transmission 32, and the guiding and supporting rollers, 25, 26 and 27, can be removed as a unit from the machine, simply by slipping the guide rods 23 and 24 out sidewise, and then lifting the complete type carriage right out of the machine, the spur gear 31 being readily disengageable from the elongated pinion 34, which drives it to permit it being removed.

The unit which comprises the clock and the automatic and manual control for the type carriage shift, is readily removable as a unit, simply by taking out the screws 249, which secure the sub-frame 101 to the main frame, and then lifting this sub-frame out, the gear 76 being readily moved out of mesh with the elongated pinion 34, to permit this removal.

The unit which carries the electromagnetic control is readily detachable and removable, simply by slipping out the pins 250 and 251, which secure the sub-frame 252 to the main frame. This sub-frame, carrying the electromagnet 38, the armature 39, the upwardly extending arm 41, and the pawl 42, can then be readily removed, the pawl 42 readily disengaging the ratchet wheel 44 to permit removal.

The ribbon feed mechanism also is readily detachable as a unit, the entire ribbon feed mechanism being mounted on a sub-frame 250^a, this mechanism including the ribbon spools 196 and 197, and the reversing mechanism 251. (Figs. 3, 5 and 7.) This sub-frame 250^a, with the parts mounted thereon is readily removable as a unit simply by tak-

ing out the screws 252* which secure it to the main frame.

The operation has been outlined in connection with the description of the construction 5 of the different mechanisms.

Briefly, if the workman is entering or leaving during a period which would be considered a "regular" period for entering or leaving, he simply inserts his card B into the card 10 holder, presses down on the handle 112, thus causing the minute, hour and day of entering or leaving to be typed on the card and then removes the card. In this operation, the lateral shift of type carriage and the vertical position 15 of the card are determined automatically by the clock controlled mechanism previously described.

If, however, the workman is entering or leaving at a time which would be considered 20 "irregular" for such arrival or departure, the type carriage will be in a position which would cause the entry to be made in the wrong column on the workman's card. Under these circumstances, the workman goes to the foreman or superintendent or whoever has charge 25 and secures from him a key which will enable him to unlock the manually operable knob 67, and shift the type carriage 22 laterally to the proper position for making the entry 30 in the right column on this card.

Having thus described my invention, what I claim as new and desire to secure by United States Letters Patent is:

1. The combination with a time recorder 35 comprising rotatable type mechanism shiftable axially to print in different positions on a card, of time controlled mechanism for periodically shifting the type mechanism having means whereby the period between shifts 40 may be varied, comprising a cam having a plurality of adjustable cam members.

2. A time recorder comprising a type carriage, a plurality of type wheels rotatably mounted on said carriage, said carriage being 45 shiftable to bring said type wheels to print in different positions on a card, means for shifting said carriage and means for operating said type wheels in any position to which said carriage may be shifted, comprising a gear 50 on said carriage and a pinion having laterally elongated teeth with which said gear meshes and along which it slides as the carriage is shifted.

3. A time recorder comprising a type carriage, type wheels mounted on said carriage, said type carriage being shiftable to cause 55 said type wheels to print in different positions on a card, time controlled means for controlling the shifting of said carriage, and manually controlled means for controlling 60 the shift of said carriage, said time controlled means comprising a rock lever, manually controlled means also comprising a rock lever, and a spring connection between said rock

levers to permit the manual control of said 65 type carriage independently of the time control of said carriage.

4. A time recorder comprising a type carriage, type wheels mounted on said carriage, said type carriage being shiftable to cause 70 said type wheels to print in different positions on a card, and manually controlled means for shifting said type carriage, comprising a rock arm, a pair of rock arms straddling said first rock arm and alternatively engageable 75 therewith, and manual means for alternatively operating said pair of rock arms.

5. A time recorder comprising a main frame, a hammer mounted on said main frame, a time controlled pinion mounted on 80 said main frame, a type carriage shiftable with respect to said main frame, type wheels mounted on said carriage, said type carriage being shiftable to cause said type wheels to print in different positions on a card, said 85 carriage having a rack mounted thereon, and a detachable unit, readily detachable as a whole with respect to said main frame, said detachable unit comprising a sub-frame mounted on said main frame, clock hands mounted on sub-frame, a cam mounted on said sub-frame for controlling the shifting of the carriage, a spur gear mounted on said sub-frame and meshing with said time controlled pinion, a spur gear mounted on said 90 sub-frame and meshing with said rack, transmission mechanism from said cam to said last spur gear, mounted on said sub-frame, transmission from said time controlled pinion to said cam, mounted on said sub-frame, transmission from said time controlled pinion to said clockhands mounted on said sub-frame, said sub-frame with all of the parts mounted thereon being detachable as a unit 95 from the rest of the structure.

6. A time recorder comprising a main frame, a shiftable type carriage, type wheels mounted on said carriage, said type carriage being shiftable with respect to said main frame to cause said type wheels to print in 100 different positions on a card, said carriage having a rack mounted thereon, a hammer mounted on said main frame, a time controlled pinion mounted on said main frame, and a unit readily detachable as a whole 105 from said main frame, comprising a sub-frame, clock hands mounted on said sub-frame, a gear mounted on said sub-frame and meshing with said pinion, transmission from said gear to said clock hands, a driving pinion mounted on said sub-frame and meshing with said rack, a manually operable member mounted independently of said sub-frame, and transmission means mounted on said sub-frame from said manually operable member 110 to said driving pinion.

7. A time recorder comprising a main frame, a shiftable type carriage, type wheels

- mounted on said carriage, said type carriage being shiftable with respect to said main frame to cause said type wheels to print in different positions on a card, said carriage 5 having a rack mounted thereon, a hammer mounted on said main frame, a time controlled pinion mounted on said main frame, and a unit readily detachable as a whole from said main frame, comprising a sub-frame, 10 clock hands mounted on said sub-frame, a gear mounted on said sub-frame and meshing with said pinion, transmission from said gear to said clock hands, a driving pinion mounted on said sub-frame and meshing with 15 said rack, a manually operable member mounted independently of said sub-frame, transmission means mounted on said sub-frame from said manually operable member to said driving pinion, a time controlled cam 20 mounted on said sub-frame, transmission from said time controlled pinion to said cam, mounted on said sub-frame, and transmission means, from said cam to said driving pinion, mounted on said sub-frame.
- 25 8. A time recorder comprising a main frame, a shiftable type carriage, type wheels mounted on said carriage, said type carriage being shiftable to cause said type wheels to print in different positions on a card, means 30 for positioning said card, mounted on said main frame, a ratchet wheel for controlling the movement of said type carriage and said card positioning means, and a unit, readily detachable as a whole from said main frame, 35 comprising a sub-frame, an electromagnet mounted on said sub-frame, an armature mounted on said sub-frame and having an arm extending therefrom, and a pawl mounted on the upper end of said arm for 40 engaging said ratchet wheel.
9. A time recorder comprising card positioning means including an oscillatable card rest with which the end edge of the card engages, and means for indicating the position 45 of the card comprising a rotatable cylinder having indicia thereon and means for rotating said cylinder, comprising a rock arm oscillatable with said card rest, a link pivotally connected with said rock arm, a 50 second rock arm pivotally connected with said link and having a segmental gear thereon and a pinion meshing with said segmental gear portion and rotatable with said cylinder.
- 55 10. A time recorder comprising a movable type carriage shiftable to print on different portions of a card, having type wheels for cooperation with a printing ribbon, a hammer co-operating with said type wheels, and 60 two guard plates adjacent said type wheels, located on opposite sides of the hammer face, and lying between the ribbon and the card, to prevent the card from engaging that part of the ribbon covered by the guard plates, one

of said guards being mounted on said movable carriage. 65

11. A time recorder comprising a movable type carriage shiftable to print on different portions of a card, having type wheels for cooperation with a printing ribbon, a hammer co-operating with said type wheels, and two flexible guards adjacent said type wheels, and located on opposite sides of the hammer face, said flexible guards lying between the ribbon and the card, to prevent 70 the card from engaging that part of the ribbon covered by said guards. 75

12. A time recorder comprising a shiftable type carriage shiftable to print on different portions of a card, having type wheels 80 for cooperation with a printing ribbon, a hammer co-operating with said type wheels, and a flexible guard mounted on said carriage and lying between said ribbon and hammer, to prevent the card from engaging 85 that part of the ribbon covered by said guard.

13. A time recorder comprising a shiftable type carriage shiftable to print on different portions of a card, having type wheels 90 for cooperation with a printing ribbon, a hammer co-operating with said type wheels, means for holding a card between said hammer and ribbon and two flexible guards adjacent said type wheels, said flexible guards 95 lying between the ribbon and the card to prevent the card from engaging that part of the ribbon covered by said guards, one of said guards being mounted on said carriage, the other being mounted on said card holder. 100

14. A time recorder comprising a type carriage, a plurality of type wheels mounted on the carriage, the type carriage being shiftable laterally to bring the type wheels to print in different positions on the card, 105 a hammer co-operating with said type wheels, said hammer having a laterally elongated face, extending longitudinally of the axis of the hammer whereby some portion of the hammer face will co-operate with the type wheels, no matter to what position the carriage may be shifted, and a stop adjacent each end of the elongated hammer face, to limit the movement of the hammer, and to cause an even pressure to be brought on the 110 type wheels. 115

15. A time recorder comprising a plurality of type wheels, for cooperation with a printing ribbon, a hammer co-operating 120 with said type wheels, and two flexible guards adjacent said type wheels and located on opposite sides of the hammer face, one of said flexible guards lying adjacent one side of the ribbon between the ribbon and the type wheels to prevent that part of the 125 ribbon overlying the guard from engaging the type wheels, and the other flexible guard lying adjacent the other side of the ribbon

between the card and the ribbon to prevent the card from engaging that part of the ribbon overlaid by said guard.

16. The combination with a time recorder comprising a rotatable type mechanism shiftable axially to print in different positions on a card, of time controlled mechanism for periodically shifting the type

mechanism, having means whereby the period between shifts may be varied, comprising a stepped cam member having means whereby the distance between steps may be varied to vary the period between shifts.

In witness whereof, I have hereunto subscribed my name.

CHARLES M. CROOK.
